FRED E. TASKER, OF NEW YORK, N. Y.

HYDROCARBON ROCK-DRILL.

No. 863,646.

Specification of Letters Patent.

Patented Aug. 20, 1907.

Application filed April 16, 1903, Serial No. 152,964. Renewed June 4, 1907. Serial No. 377,263.

To all whom it may concern:

Be it known that I, JOHN V. RICE, Jr., a citizen of the United States of America, and a resident of Edge-water Park, in the county of Burlington, State of New Jersey, have invented certain new and useful Improvements in Hydrocarbon Rock-Drills, of which the following is a specification.

My present invention relates to an improvement in hydrocarbon or gas-actuated rock drills, its object 10 being to provide a simple and effective drilling mechanism, which will develop a very high efficiency in operation, but can be run economically because of the character of the fuel and the nature of the explosive motor that drives the tool; and the invention consists 15 essentially in the construction, arrangement and combination of parts, substantially as will be hereinafter more fully described and claimed.

In the annexed drawings illustrating my invention, Figure 1 is a side elevation, in partial section, of my 20 improved hydrocarbon rock drill. Fig. 2 is a horizontal section of the same. Fig. 3 is a similar horizontal section of a portion of the mechanism, showing the piston rod or the drill-carrying rod in a different position relatively to the actuating piston from that which 25 it occupies in Fig. 2. Fig. 4 is a cross-section on the line *xx* of Fig. 3. Fig. 5 is a detail end view of one of the sectional rings. Fig. 6 is an enlarged view in detail, delineated somewhat conventionally, representing the different parts of one example of igniting 30 device. Fig. 7 is a horizontal sectional plan view of a modification of the invention. Fig. 8 is a side elevation similar to Fig. 1, and Fig. 9 a detail plan view, of certain parts, both figures showing certain modifications in the construction and arrangement. Fig. 10 35 is a sectional view of another modification of the yielding device bearing against the piston rod.

Similar numerals of reference designate like parts, throughout all the figures of the drawings.

1 denotes the main cylinder, which may be of any 40 suitable or preferred design and form, being generally open at one end and closed at the other, and made either with or without a water jacket. At the closed end is the explosion chamber 40, while the other or open end is formed with an integral, barrel-like extension 45 7, which serves as a guide and support for the outer end of the elongated piston 12. Said cylinder extension 7 is provided with longitudinal slots 8, 8, formed opposite to each other and receiving the sliding blocks 9, 9, which are designed to reciprocate in said slots as 50 guides. The blocks 9 are engaged by pins or studs 11 that pass through round orifices in the blocks and that project laterally from the piston 12, being screwed into the latter, as shown in Fig. 2, or otherwise rigidly

attached thereto or made a part thereof. Piston 12 is of a hollow elongated pattern or type, one end entering 55 and working within the cylinder 1, where it receives against itself the impact due to the successive explosions of the mixture of air and gas ignited in the combustion chamber 40; while the other end of this long piston plays back and forth inside of the hollow extension 7 and carries the piston-rod or drill-supporting rod 18, the means for imparting rotation to said rod, and the means for cushioning the blow of the tool. This rod 18 has on its outer end the drill-chuck 16 adapted to hold any suitable drill or other tool; also 60 it has a shoulder 18^a which is adapted to abut against the outer end of piston 12 at certain times. The exterior surface of the drill-supporting rod 18, which rod may also be termed the piston rod, is, between the chuck 16 and the shoulder 18^a, slightly rounded 65 70 dished, or concaved at 17, making it, as it were, in the shape of a spool, for a purpose to be presently explained. Piston rod 18 moves obviously with the piston 12, but it also has a secondary movement within the piston, and to its inner end is securely fastened an 75 inner sliding block 20 that reciprocates in the chamber 21 in piston 12, see Figs. 2 and 3. Further rod 18 has a central bore 19, and the inner sliding block 20 is perforated similarly to coincide with bore 19.

Means are provided to impart a rotation to the drilling 80 implement or other tool by rotating the rod 18 which carries it. In the present example of my invention said means are carried by the piston and consist of a spirally-grooved rod 15 engaging internal ribs or pins within block 20, on the end of which grooved rod 15 85 is a ratchet wheel 14 contained within a ring 27 stationary inside the piston 12, the end of the piston adjoining the ring 27 being closed by a screw plug or head 13 that screws tightly into the piston against the ring 27. Suitable pawls 28, see Fig. 4, acted on by springs 41, 90 engage the teeth of ratchet wheel 14 and prevent it from revolving in one direction though permitting it to turn freely in the other; so that when the piston is traveling in one direction—preferably the up-stroke—the tool will be partially rotated, but when the piston 95 travels in the opposite direction—preferably the down-stroke—the drill will pursue a rectilinear and non-rotary movement; it being apparent that the grooved rod 15 will have no endwise movement relatively to the piston 12, because the ratchet 14 pulls tightly 100 against the flange of ring 27, although the piston rod 18 in its secondary movement slips freely back and forth on that portion of rod 15 which lies within the bore 19, wherein rod 18 revolves or not, as stated. And it will 105 thus be seen that the means for rotating the drill are not brought into action directly by the reciprocation

of the piston, but by the rod's return movement after the additional yielding movement of the piston rod which produces the cushion effect.

The cylinder 1 and connected parts are carried by some suitable supporting frame, as 42, on which they are adjustable by a screw 43, or by some other equivalent and convenient device; in connection with which the usual tripod support may be utilized.

It becomes of the greatest importance in a drill of this kind, which is used in boring holes in rocks of all degrees of hardness and flintiness, to find some way of mitigating the intensity of the blow of the drill upon the rock without at the same time impairing its cutting power; for without some means for rendering the action of the drill more or less elastic the machinery would be strained and racked so seriously as to ruin it in a short time, and this would be especially so if it were run at the very high rate of speed now generally demanded for the rapid prosecution of the different lines of work which involve the use of rock drills. In order to effectually cushion the movement of the drill and provide the requisite elasticity, I provide an elastic connection between the piston and the piston-rod, which connection may consist of means carried by the piston for causing a lateral yielding pressure against the piston-rod, or means carried by the piston rod for causing a lateral yielding pressure against the piston, so as to regulate the rectilineal movement of the piston-rod and thus subdue the violence without materially detracting from the strength of the blow of the tool. One form of this means consists of a series of springs 22 arranged around the drill-carrying rod and pressing upon and against the side of the latter for the purpose of making the movement thereof yielding and easy. These springs 22 may consist of a single leaf or a plurality of leaves. Their free ends have cup bearings 23 carrying anti-friction balls 24 that travel on the concave line 17 of the spool portion of rod 18, thus preventing friction and giving a strong and even pressure. The inner ends of springs 22 are preferably bent to take into notches 58 on the outside of piston 12, and are held in this position by the sleeve 25 which screws over the end of piston 12 and is interiorly beveled, there being a sectional beveled ring 26—see Fig. 5—between sleeve 25 and springs 22 which is tightened more or less against the springs by the screwing up of the sleeve 25 upon and against the sectional ring 26, whereby the springs 22 are caused to bear with greater or less tension against the side of rod 18.

Bolted to the cylinder 1 in any suitable manner is a frame or casting 2, which provides the head of the cylinder if desired, as shown, and also which affords a substantial bearing across the end of the machine for a main transverse shaft 3, a bushing being preferably placed in the bearing for the easy running of the shaft. This shaft has on each end a fly wheel 4 provided with a crank pin 4^a. Two fly-wheels are preferred, but one may be used if desired. Connecting rods 10, extend from the pins 4^a to the piston-carried pins or journals 11. On the shaft 3 is a worm 5 that meshes with and drives a small worm pinion 6 on a shaft 29 supported at right angles to shaft 3 in suitable bearings in frame 2.

The frame of casting 2 contains an inlet chamber 69 having an induction opening 71 entered by a pipe or passage leading from the vaporizer and the gasoline or

hydrocarbon tank to supply the requisite explosive mixture of air and gas to the cylinder. 33 denotes the inlet valve for the air and gas, opening from the chamber 69 to the explosion chamber 40, said valve being carried by a stem 35, having a closing spring 72, while the end of the stem projects into a position to be struck by the cam 31 on the shaft 29; and 32 denotes the exhaust or outlet valve for the spent products of the explosions, leading from the explosion chamber 40 into the exhaust chamber 70 and thence to atmosphere through some suitable vent or eduction port, said valve 32 having a stem 34 provided with a closing spring 73, while the end of the stem 34 projects into a position to be struck by another cam 30 which is fast on the shaft 29; the said two cam devices 30 and 31 being so arranged relatively to each other, projecting as they do in different directions, that when one is acting on the end of one valve stem for the purpose of opening its valve, the other will be inactive and exert no pressure against the stem of the other valve; that is to say, when the inlet valve is open the exhaust valve will be closed, and when the exhaust valve is open the inlet valve will be closed.

Any suitable sparking mechanism may be utilized to explode the charge of air or gas after it has been introduced into cylinder. I do not wish to be restricted to any particular kind. Ordinarily I have employed a common spark plug, see Fig. 6, in which 54 indicates the insulation surrounding it; 53, the plug proper; and 51, the adjustable screw forming one of the electrodes 95 or contact points; while 52 denotes a spring finger forming the other electrode and projecting into the explosion chamber alongside the screw 51 so that a spark will be produced between the points of the two electrodes when the electrical circuit is closed. A 100 wire runs to the outer end of the finger 52 and another wire to the outer end of the screw 51. On the shaft 29 is a rotary cam 47, fixed thereto and revolving therewith. During each revolution it strikes against a spring finger 49 which is carried by an adjustable arm 105 45, one end of which is hung loosely on shaft 29. The other end of the adjustable arm 45 has therein a pin 46 which passes through a slotted stationary segment 44 and is provided with a set screw 48 for clamping arm 45 to the segment 44 at any desired position of 110 adjustment. The spring 49 is insulated by means of the insulating material 75 through which pass binding screws 74, 74, to which are attached electric wires. Spring 49 connects with one of the binding screws 74, while the other binding screw 74 carries the plate 50. 115 into contact with which the finger 49 is brought at each revolution of the cam 47, thereby causing the electric circuit to be closed. Hence, the timing of the spark may be regulated by the adjustable arm 45 which, by a change of position, places the finger 49 in 120 different locations and thus enables the cam 47 to act earlier on the spring 49 when it is in one position than when it is in another position; all as will be readily understood upon inspection of the relative arrangements of the parts in Fig. 6.

In Fig. 7 I have represented a modification of my invention. The changes consist principally in a different form and arrangement of the means for elastically or yieldingly connecting together the drill-supporting rod and the actuating piston. In Figs. 1, 2 and 3 it has 130

been seen that the yielding means on the piston tightly grips the sides of the drill-supporting rod in order to enable the blow of the drill to be cushioned. In the present modification there is a reversal of the arrangement, in that a yielding means on the drill-carrying rod grasps, or tightly hugs, a portion of the piston, although there is a like freedom of movement between the drill-supporting rod and the piston as exists in the form of the invention in Figs. 1, 2 and 3. Proceeding now to 10 describe more particularly the construction and combination disclosed in Fig. 7: 55 denotes the cylinder having preferably a water jacket 56, though this may be omitted if desired; as in Figs. 1, 2 and 3, there is the explosion chamber 40, a sparking device, the main- 15 shaft 3 carrying fly-wheels 4 and having worm 5 engaging pinion 6 on shaft 29, and also the connecting rods 10, 10 which communicate motion from the piston to the fly-wheel. 57 designates a modified piston, one end of which is within the cylinder 55, while the other 20 slides within the cylindrical extension 60 of the cylinder, that forms a guide for the movement of the piston, said extension 60 having oppositely located elongated slots 59, 59 that receive integral projections 58 on the piston 57, which projections 58 are loosely connected 25 to the connecting rods 10. The drill-carrying or piston rod 61 has the same chuck 16 as the drill-carrying rod 18 in Fig. 1, and carries a series of springs 66, each consisting preferably of several leaves, the free ends of said springs 66 being provided with cup-shaped bear- 30 ings containing balls 67, while the other ends of the springs are secured to the drill-carrying rod 61 by means of the internally screw-threaded sleeve 76 that fits neatly into and slides within the guiding extension 60, there being a sectional beveled ring 77 between the 35 sleeve 76 and the springs 66, the interior surface of said sleeve 76 being correspondingly beveled, and the function of the intermediate ring being to make the tension of the sleeve greater or less according to the adjustment of the parts. The balls 67 carried by the springs 66, 40 like the balls 24 carried by the springs 22 in Fig. 1, bear upon a concave surface, but said surface instead of being on the drill-carrying rod as in Fig. 1 is on the central portion 68 of the piston 57. This piston is hollow, as shown, and is shaped to present this integral central 45 portion, against which the pressure of the yielding fingers on the drill-carrying rod may be brought. Said central portion 68 is hollow, being provided with a cylindrical bore 78 to receive the end 62 of the drill-carrying or piston rod 61, said end being hollow at 50 63 and fitted at the end with a sleeve 79 which is screwed thereinto, as shown in Fig. 7. A spirally-grooved rod 64 enters the bore 63 in the part 62 of the piston rod 61, passing through the inserted sleeve 79, and the groove in rod 64 engages one or more lugs, pins or ribs on the 55 interior of the sleeve 79, or within the bore 63; and said spirally-grooved rod 64 is attached to a ratchet wheel 65 that works in combination with a pawl 80, said ratchet 65 and its pawl being held within a recess in the piston 57 by means of a cover or plate 81. It will be 60 understood, of course, that the piston 57 reciprocates in consequence of the blows exerted thereon by the explosions of the mixture of gas and air and that the grooved rod and ratchet device impart intermittent partial rotations to the piston rod on each reverse move- 65 ment of the latter or upstroke of the piston; and

furthermore, that the cushioned connection between the piston rod and the piston acts with substantially the same function and effect as is the case with the mechanism represented in Figs. 1, 2 and 3, the whole object of the yielding combination being to enable the blow of the drill to be struck with greater ease, but no less power. 70

In Figs. 8 and 9 I have shown another modification in the arrangement of the pressure devices acting against the side of the piston rod. 76 denotes a rod the 75 same having a bent inner end engaging a notch on the piston and held loosely in place by the screw ring 77. These rods are preferably single and not a multiple construction. There is preferably one rod located on one side of piston rod 18 and another one situated opposite on the other side. At the outer end of each rod is secured a cross piece 79, and between the ends of these cross pieces are arranged spiral springs 78, the ends of the springs passing through said cross-pieces and being held in place at one end by ordinary nuts and, at the other end by thumb nuts 80, the latter permitting the tension of the springs to be regulated. Between the cross pieces 79 and the sides of the drill carrying- 80 rod 18 are small-balls or rollers 81. The provision of the transverse spiral springs connecting the ends of rods 76 85 90 will be found serviceable for many purposes.

Still another modification is represented in Fig. 10 where a tube 82 is screwed upon the end of the piston. The outer end of this tube has a beveled flange 86. Inside the tube is a sliding ring 84 having a beveled 95 edge. A spiral spring 83 is tensioned between the piston and the ring 84. Between the beveled edges of ring 84 and of the end of tube 82 is arranged a series of anti-friction balls 85. Thus the spring 83 presses the balls 85 against the concave surface 17 of the piston rod 100 and affords a yielding connection between the piston rod and the piston.

Having thus described my invention what I claim as new and desire to secure by Letters Patent, is:—

1. In a rock drill, the combination of a cylinder, a piston therein, a piston rod having a movement with the piston and a secondary movement inside of the piston, means carried by the piston for imparting a rotation to the rod, and elastic means connecting the piston and piston rod, consisting of a yielding rolling device on one element en- 105 gaging a curved face of the other. 110

2. In a rock drill, the combination with an explosion cylinder, and a piston therein, of a piston rod having a movement with the piston and a secondary movement inside of the piston, and elastic means connecting the piston and piston rod, said means consisting of springs on one element and exerting a yielding effect against the other element, and means carried by the piston for imparting a rotation to the rod. 115

3. In a rock drill, the combination with an explosion cylinder and a piston therein, of a piston rod, having a concave face, and elastic means connecting the piston and piston rod, consisting of springs on the piston, together with rolling devices between said springs and the concave face of the piston rod. 120

4. In a rock drill, the combination of a cylinder, a piston, a piston rod having a movement with the piston and a secondary movement inside of the piston, means on the piston for exerting a pressure against the side of the rod to cushion the blow of the tool, said means consisting of springs, and means carried by the piston for imparting a rotation to the rod. 125

5. In a rock drill, the combination with an explosion cylinder and a piston therein, of a piston rod having a concave face, means carried by the piston for imparting a 130

- rotation to the rod, and elastic means connecting the piston and the piston rod, said means consisting of springs of one element and bearing laterally against the other.
6. In a rock drill, the combination with an explosion 5 cylinder and a piston therein, of a piston rod carrying the drilling tool, means carried by the piston for imparting a rotation to the rod, and means on the piston for exerting a pressure against the side of the rod, said means consisting of springs having cup-shaped ends, together with balls situated between said ends and the concave face on the piston rod.
7. In a rock drill, the combination of a cylinder, a piston, a piston rod having a movement with the piston and a secondary movement inside of the piston, means on the 10 piston for exerting a pressure against the side of the rod to cushion the blow of the tool, and means carried by the piston for imparting a rotation to the rod, said means consisting essentially of a rod having inclined grooves and a ratchet device.
8. In a rock drill, the combination of a cylinder, a piston, a guide on the cylinder for the movement of the piston, a main shaft having a wheel thereon, a connection between said wheel and the piston, a piston rod slidable within the piston and having a movement with the piston 15 and a secondary movement inside of the piston, means for yieldingly connecting the piston rod to the piston, and means carried by the piston for imparting rotation to the rod.
9. In a rock drill, the combination of a cylinder having an extension forming a guide, a piston in said cylinder and guide, a piston rod for carrying the tool, elastic means on the piston for exerting a yielding pressure against the side of the piston rod, and means including a ratchet device carried by the piston for rotating the piston rod.
10. In a rock drill, the combination of a cylinder having a guide, a piston in said cylinder and guide, a piston rod having a movement with the piston and a secondary movement inside of the piston and carrying the tool, means on the piston exerting a pressure against the side of the rod 20 to cushion the blow, said means consisting of springs carrying rolling devices working against the concave face of the piston rod, and means carried by the piston for rotating the piston rod consisting of a grooved rod entering the recess in the piston rod and provided with a ratchet and pawl device arranged in a recess in the piston.
11. In a hydrocarbon rock drill, the combination of a 25 cylinder having an extension providing a guide, a piston rod slidable within the piston for exerting a yielding pressure against the side of the rod to cushion the blow of the tool, and means carried by the piston for imparting a rotation to the rod.
12. In a hydrocarbon rock drill, the combination of a cylinder, a piston, a piston rod having a movement with the piston and a secondary movement inside of the piston, means on the piston for exerting a pressure against the side of the rod to cushion the blow of the tool, and means carried by the piston for imparting a rotation to the rod.
13. In a hydrocarbon rock drill, the combination of a cylinder, a piston, a piston rod for supporting the tool or 30 implement, said rod moving with the piston and having a secondary movement relatively to the piston, means on the piston pressing against the side of the piston rod and consisting essentially of springs acting against a concave face of the rod and means carried by the piston for imparting a rotation to the rod.
14. In a hydrocarbon rock drill, the combination of a cylinder, a piston, a piston rod moving with the piston and having a secondary movement relatively to the piston, said rod moving inside of the piston and carrying therein 35 a sliding block, means for rotating the piston rod, said means consisting of a grooved rod inside the piston rod and provided with a ratchet and pawl device located in a recess in the piston, and means for cushioning the blow of the tool consisting of springs on the piston exerting a pressure upon the rod so as to make its rectilinear movement elastic.
15. In a hydrocarbon rock drill, the combination of a cylinder having an extension providing a piston guide, a hollow piston in said cylinder and guide, a piston rod 40 slidable within the piston and carrying a block inside of the latter, said rod having a movement with the piston and a secondary movement inside of the piston, means carried by the piston for imparting a rotation to the rod, consisting of a spirally grooved rod and a pawl and ratchet, and spring means on the piston exerting a lateral pressure within a concaved face of the rod to control the rectilinear movement of the latter.

Signed at New York city this 9th day of April 1901.
